DISPLAY STAND FOR COSMETICS

Ben Walker, 18 Oswego Ave.,
Oakland, N.J. 07436

Filed June 21, 1966, Ser. No. 2,769

Term of patent 14 years

(Cl. D80—9)

FIG. 1 is a front perspective view of a display stand for cosmetics, showing my new design; the back thereof being essentially plain and unornamented;

FIG. 2 is a side elevational view taken from the right of FIG. 1; and

FIG. 3 is a top plan view.

I claim:

The ornamental design for a display stand for cosmetics, as shown and described.
